UNITED STATES PATENT OFFICE

MORRIS M. EINSON, OF YONKERS, NEW YORK, ASSIGNOR TO EINSON-FREEMAN CO., INC.,
OF LONG ISLAND CITY, NEW YORK, A CORPORATION OF NEW YORK

DISPLAY DEVICE

Application filed October 5, 1931. Serial No. 566,841.

The present invention relates to collapsible card display devices useful for advertising merchandise and other things. An object of the invention is to provide a device simple in operation and economical in manufacture, and another object is to provide means for supporting the device in its erect or set up position.

According to the present invention the improved device is composed of two or more sheets of paper-board, one sheet forming a supporting body for a plurality of added sheets in the form of display cards or the like which are secured to said supporting body in such a manner that one card will stand above and back of another card so as to produce a tier or stepped relation therebetween. The cards are prepared so as to represent a number of cartons for merchandise or other objects arranged in rows and collectively said rows can be prepared and arranged to produce the effect of a stack forming a pyramidal or other shaped structure. Said supporting body is collapsible so that the device will fold into a flat position; means being provided on said body for retaining the same in the set up or erected position and said body carries means forming an extended base or support for the device so that it will stand firmly in an upright display position.

The invention will be more fully described hereinafter with reference to the accompanying drawing; wherein—

Figure 1 is a front elevation of the improved device shown in its standing or display position;

Figure 2 is a rear elevation showing the device in the collapsed position;

Figure 3 is a sectional view taken on line 3—3 of Figure 1;

Figure 4 is an enlarged side elevation partly in section showing the improved device in the erected and display position;

Figure 5 is also an enlarged elevation showing the device in the collapsed position; and

Figure 6 is a fragmentary view showing a modification.

Referring to said drawing, 1 is the body

having a back wall 2 and side walls 3. The body 1 is provided with a step or steps 4, it being understood that according to requirements any reasonable number of steps may be provided. The stepped vertical portions of the side walls 3 have flanged edges 5 which offer means for securing the display cards 6 in position. These display cards are preferably glued to said flanges and when in position stand one above and behind the other.

The back wall of the body 1 has an extension 7 standing above and behind the top-most display card 6 and this extension 7 operates as another display card standing prominently above the others so as to be a valuable adjunct as an advertisement in conjunction with said display card or cards 6. The body 1, as stated, is collapsible being foldable on crease lines 8 located at points where the back wall 2 is connected to the side walls 3 and at the points where said side walls are connected by the glue laps 5 to the display cards 6. The body 1 with the back wall, side walls and the front display cards secured thereto forms a tubular collapsible structure and when erect both ends of said structure are open. No closure means are required for said open ends and which closure means with devices of a similar kind in common use are employed to retain the body in its erect or set up position. In lieu of such closure means located at the ends of the body, a folding strip 9 is partly cut from the back wall and arranged to hinge thereon. This retaining strip is placed at a point intermediate of the two ends of the body and when folded inwardly at right angles to said back wall, the free edge thereof will bear against the back of one of the secured display cards and thereby effectually hold the device in its set up position.

Display devices of the kind to which the improved device belongs are usually of a comparatively shallow depth and may be comparatively high; therefore an extended base must often be provided to hold the device firmly in a standing position. An improved device for this purpose is designed and said device consists of integral portions

- cut out from the back wall 2 and these portions open outwardly so as to provide feet 10 extending backwardly from the side walls of the device. As shown in Figure 2, these feet 5 10 lie flat when the device is collapsed and therefore these feet are not weakened by any creased or folding lines and will at all times project rigidly outwardly from the back wall thereby providing a rigid and firm base on 10 which the device will stand firmly against any danger of falling over under reasonable conditions.

The improved device, it will be noted, is very simple in construction and the several 15 parts thereof may be assembled and secured by machine operation. In the manufacture of the device the blank forming the body is folded on the crease lines 8 and the display cards are located and adhesively secured by 20 means of the glue laps 5. The display card or cards 6, after passing through the machine or hand-folding operation, lie in the flat condition and are so delivered to the packer. When setting up the device the operator need 25 only open the collapsed body and press down the retaining strip 9 into its operative position. Collapsible tubular supports for display cards etc. have previously been proposed but in all known instances the structure is re- 30 tained in its set up position by the end closure device. These end closing devices are formed of extensions from the blank and therefore both consume and waste a great deal of stock and besides the manipulation 35 of these devices requires a number of operations. With the present retaining means the strip 9 being cut from the back wall consumes no extra stock at all and one simple quick operation will set the retaining strip in its 40 operative position. With this strip located at a point intermediate, the effect produced by this retaining device so located is for practical purposes equal to what would be obtained by employing closure means at both 45 ends of the body. To further facilitate the operation of this strip 9 a portion is cut out at 11 to create a finger opening.

It will be understood that the improved retaining device can be employed separately 50 without the bottom support for at times the bottom dimension of the tubular body may be sufficient to form in itself a firm base for the structure. In some instances it may be desirable to use an easel as shown in Figure 6. 55 Herein the easel 12 is secured to the back wall of the device and this easel has a non-folding tab 13 extending therefrom and located in alignment with the opening 14 which is left by partially cutting out the retaining strip 9. The easel in its closed position lies flat 60 against the back wall but when opened, the easel stands at right angles to said back wall and said tab 13 will pass through the opening 14 and stand above the folded down strip 9 65 where it will operate to prevent the self-

closing of the strip 9 to allow the structure to collapse.

Modifications may be made in carrying out the details of the invention hereinbefore described and it is to be understood that any modification coming fairly within the terms of the appended claims shall be covered thereby.

I claim:

1. A display card device and support therefor, said support being of a tubular form having a back wall, side walls and open ends, said side walls having steps, a display card secured to each step in front thereof, a portion cut from said back wall folding within said body so that the free end of said cut out portion bears against the back of a display card whereby said body is maintained in the set up position, and rigid or non-foldable portions cut from said back wall forming feet 75 80 85 projecting from said side walls providing an extended base for said body.

2. A display card device and support therefor, said support being of a substantially tubular form having a back wall and side walls, 90 said side walls having steps, display cards secured to said steps in front thereof, and rigid or non-foldable portions cut from said back wall forming feet projecting from said side walls providing an extended base for 95 100 said device.

In testimony whereof I affix my signature.
MORRIS M. EINSON.
